[57] CLAIM

The ornamental design for a shoe guard, substantially as shown and described.

DESCRIPTION

FIG. 1 is a front elevational view of a shoe guard showing my new design;

FIG. 2 is a cross-sectional view thereof as taken from line 2—2 of FIG. 1, this lower portion and attachment straps having been omitted for ease of illustration;

FIG. 3 is a cross-sectional view thereof as taken from line 3—3 of FIG. 1, the attachment straps having been omitted for ease of illustration;

FIG. 4 is a right side elevational view thereof with the strap perpendicular to the front of the guard, the left side being a mirror image thereto.
